RADIO RECEIVING SYSTEM

Vernon D. Landon, East Pittsburgh, Pa., assignor
to Westinghouse Electric & Manufacturing
Company, a corporation of Pennsylvania

Application November 14, 1928, Serial No. 319,234

11 Claims. (Cl. 250—9)

My invention relates to radio receiving systems and apparatus, and it has particular relation to systems wherein signals received upon a single energy receptor are distributed to a plurality of indicating devices.

- The problem of distributing radio programs to the individual apartments of a large apartment house, or to the rooms of a hotel or similar building, is one that insofar as applicant is aware 10 has not hitherto been solved in an entirely satisfactory manner. It has been proposed to receive the radio signals at a central station, and to distribute the programs at audio-frequency over a plurality of separate channels connected to the various apartments, but the number and variety 15 of programs thus available to the tenants through such a system is obviously limited. Furthermore, the initial cost of an audio-frequency distribution system, if more than one or two separate programs are to be made available, is high, and a skilled attendant must be kept always available to supervise the tuning of the receiving apparatus and to adjust the amplifiers feeding the distribution network.
- 20 It is, accordingly, an object of my invention to provide a distributing system whereby an unlimited number of radio programs may be made simultaneously available in any one of a plurality of rooms of a building.
- 25 Another object of my invention is to provide a distributing system of the type described wherein the programs are simultaneously transmitted to the several rooms by means of radio-frequency currents.
- 30 Another object of my invention is to provide, in a radio-frequency program-distributing system, means for preventing interaction, and consequent interference, between the individual receiving sets coupled to the distribution network.
- 35 Another object of my invention is to provide, in a radio-frequency program-distributing system, means for preventing any one of the individual receiving sets coupled to the distributing network from adversely influencing the reception of signals by any of the other receiving sets.

Another object of my invention is to provide a system of the type described through the use of which programs may be distributed by means of radio-frequency currents without detrimental 40 attenuation.

Another object of my invention is to provide, in a system of the type described, means for preventing local extraneous disturbances from interfering with the reception of signals.

55 Another, and more specific object of my in-

vention is to provide, in a system of the type described, means whereby the elements constituting the distribution network for radio-frequencies may be utilized for conveying direct current from the central station to the locations where individual radio receiving sets are installed.

In the particular embodiment of my invention shown in the drawing, I provide a single energy receptor, or antenna that is rendered aperiodic by the inclusion therein of a high resistance device. 10 A plurality of amplifier tubes are so disposed with reference to the resistance device that a portion thereof constitutes the input circuit of each tube, the number of tubes being chosen to equal the number of the wings, or sections, of a 15 building that are to be supplied with signal-energy at radio-frequencies.

The output circuit of each of the amplifier tubes, which will hereinafter be referred to as antenna-coupling tubes, comprises the primary 20 winding of a step-down transformer, the secondary of which constitutes the input impedance of a double-conductor transmission line. The midpoint of the secondary winding is connected to ground through a resistor. The midpoint of 25 a terminal impedance device which is connected across the far ends of the transmission line is also grounded through a resistor and a condenser.

Each transmission line is enclosed in a conductively-grounded metallic conduit thereby preventing 30 the line from picking up stray disturbances, caused by sparking elevator-control contacts, etc., the conduit being also utilized for the transmission of plate-potential from a central station throughout the building.

At each point where the transmission line is to be provided with a branch connection, or where the high-frequency signals are to be demodulated and rendered audible, an individual 35 coupling tube is provided, the input circuit of each tube being connected between one of the conductors constituting the transmission line and the grounded conduit.

The novel features that I consider characteristic 40 of my invention are set forth with particularity in the appended claims. The invention itself, however, both as to its organization and the theory upon which it is based, together with additional objects and advantages thereof, will best be 45 understood from the following description of a specific embodiment, when read in connection with the accompanying drawing:

The single figure of the drawing is a dia- 50 grammatic view of a portion of a radio-frequency 55

signal-distributing system comprising a preferred embodiment of my invention.

The apparatus illustrated in the drawing comprises an energy receptor circuit constituted by an antenna 1, a condenser 2, a high resistance device 3 and a ground connection 4. The condenser and resistor are preferably enclosed in a metallic container 5 that, for best results, is disposed closely adjacent to the antenna, on the roof of a building.

A grounded metallic container 6 is disposed closely adjacent to the container 5, and in it are mounted an antenna-coupling-tube 7, a filament-supply transformer 8 and a radio-frequency transformer 10. A resistor 11 is connected across the filament terminals of the coupling-tube, the central point on the resistor being connected to the metallic container through a large condenser 12.

20 The grid of the coupling-tube is connected to the antenna resistor by a conductor 13, a coupling condenser 14 being interposed in the connection. The tube is provided with a grid-leak resistor 15, as is customary.

25 The central point on the filament-shunting resistor 11 is connected through a second resistor 16 and a conductor 17 to the negative terminal of a source 18 of high potential. The high-potential source 18, which may be a B-eliminator of any 30 well-known type, or which may be a battery, if desirable, is preferably enclosed in a grounded metallic container 20, to which the positive terminal of the source is connected.

35 The plate of the coupling-tube is connected to ground through the primary winding of the radio-frequency transformer 10. The midpoint of the secondary winding of the transformer 10 is connected to ground over a path including a resistor 21, a conductor 22, the resistor 16, and the condenser 12 that serves to connect the midpoint of the filament-shunting resistor 11 to ground.

40 The secondary winding of the transformer 10 constitutes the input-impedance of a transmission line comprising a plurality of conductors 23 and 45 24. The conductors may be the usual twisted "flex", the inter-conductor capacity of which is definite and does not change appreciably over a given length.

45 The transmission line is divided into a plurality 50 of sections, and in each section a loading inductor 25 is inserted in each side of the line. The length of a section is determined by the capacity between the two sides of the line in that section. The capacity between the conductors of the line 55 in any given section should be, for best results at the radio-frequencies now used for broadcasting, of the order of 400 micro-microfarads.

60 The transmission line terminates in a fixed resistor 26 preferably mounted in a grounded 65 metallic container 27. The midpoint of the resistor is connected to the container through a resistor 28 and a condenser 30.

65 The transmission line is preferably supported within, and insulated from, a metallic conduit 70 31. A plurality of branch conduits 32 are connected to the main conduit 31, each branch conduit extending to a location where an individual receiving set is to be installed, at which location a grounded, metallic, apartment-coupling-tube container 33 is positioned.

75 A coupling-tube 34 is mounted within the container 33. The output circuit of the tube includes the primary winding of a radio-frequency transformer 36, similar to the transformer 10, supported within the container. The filament of

the tube is supplied with current from the secondary winding of a filament-heating transformer 37 which is mounted within the coupling-tube container. A switch 38 is preferably included in the connection between the primary winding of the transformer and a source of potential therefor, the switch being disposed exteriorly of the container in order that the coupling tube 34 may be energized at will.

80 The secondary winding of the radio-frequency transformer 36 connects to two terminals 40 and 41, disposed exteriorly of the container, from which terminals leads may be taken to the antenna and ground binding posts of a suitable radio set, preferably of the type having a resistive input 15 circuit of about 2000 ohms.

85 One side of the transmission line 23-24 is connected to the grid of the apartment-coupling tube by means of a conductor 42, the conduit 31 being connected to the filament of the tube over a path which includes a conductor 43, a large condenser 44, and a resistor 45 disposed in shunt to the filament terminals.

90 The grid of the tube 34 is connected to the filament thereof over a grid-leak path including an inductor 46 and a resistor 47. Plate potential for the tube is supplied from the source 18 over the conduit 31 and the conductor 43 that connects the plate to the conduit, the plate-return path comprising the filament shunting resistor 45, the grid-leak resistor 47, inductor 46, and the wire 24 of the transmission line to which the grid is connected.

95 The radio-frequency transformer mounted in the antenna-coupling-tube box is of the step-down type in order that the impedance of the transmission line may be given a low value for reasons which will later be given in more detail. The transformer mounted in the apartment-coupling-tube box is also of the step-down type.

100 As many antenna-coupling-tube boxes as are necessary to properly distribute the signals may be associated with the high resistor included in the antenna circuit. Inasmuch as each antenna-coupling tube has one-way conductivity, no interference results between the several distribution lines.

105 In order that the drawing shall not be too complicated, I have illustrated only two-antenna coupling-tube boxes, but this is not to be construed as limiting the number of such boxes that may be employed. It will be noted from an inspection of the drawing, however, that a separate plate-potential source should be provided for each antenna-coupling tube box and the individual 110 apartment-coupling tube boxes associated with the transmission line energized thereby. Such an arrangement is not expensive, inasmuch as each of the plate-supply units may take the form of a B-battery eliminator of simple design.

115 In order that the operation of a signal-distributing system constructed and arranged according to my invention shall be fully understood, it is considered best to digress somewhat at this point and to briefly outline the theory upon which my 120 invention is based.

125 The design is based to some extent on the principle underlying a low-pass filter or loaded transmission line. The formulas applying to this circuit are:

$$(1) \quad R_T = \sqrt{\frac{L}{C}}$$

$$(2) \quad f_c = \frac{1}{\pi \sqrt{LC}}$$

where f_c is the cutoff frequency, and R_t is the terminal resistance. Higher frequencies than the cut-off frequency are attenuated to a degree which increases rapidly as the frequency is increased. Lower frequencies are transmitted with practically no loss.

If E volts are applied at a frequency lower than f_c in series with an initial resistor R_t (commonly called the generator resistance) then

$$10 \quad \frac{E}{2}$$

volts will appear across the terminal resistor R_t providing the circuit is so balanced that Equations (1) and (2) are fulfilled.

These same formulae apply to a grounded-neutral circuit, such as that shown in the drawing, when the inductance used for L is that of the two loading coils of one section of the line in series, and the capacitance used for C is the capacitance of one side of the line to the other side, for a single section between loading coils. The distributed inductance of the wires is negligible in this case as telephone twisted-pair wires are used and there is very little space between wires.

We, therefore, must solve a pair of simultaneous equations with four unknowns. Clearly, arbitrary values may be assigned to any two of the variables and the corresponding values of the other two variables may then be determined by the two equations.

The most important factor is f_c . A convenient value, for arithmetical simplicity and for practical reasons for f_c , is 1,570,000, or

$$35 \quad \frac{\pi}{2} \times 10^6$$

cycles. Substituting this value in Equation 2 gives

$$40 \quad f_c = \frac{1}{\pi\sqrt{LC}}$$

or

$$45 \quad \frac{\pi}{2} \times 10^6$$

Solving this equation,

$$\sqrt{LC} = \frac{2}{10^7}$$

or $LC = 4 \times 10^{-14}$.

If a convenient value is next assigned to either L , C , or R , the other two values will then be determined by the above equations.

It is most convenient to have the loading-coils spaced a distance apart equal to a multiple of the distance between the floors in the building which the system is installed since the coils may then be placed in the coupling-tube boxes and special boxes need not be provided. If the floors are approximately 10 feet apart, a loading-coil spacing of 20 to 22 feet is desirable. This length of #18, telephone, twisted-pair line has an inter-wire capacity of a little over 300 mmmfd. Allowing about 50 mmmfd. apiece for two coupling-tubes (the average number per section of line) gives a line capacity of 400 mmmfd. per section. Substituting this value in the equation $LC = 4 \times 10^{-14}$, we have

$$L = \frac{4.10^{-14}}{400 \times 10^{-12}}$$

70 or 100 microhenries. R_t is then fixed, by the equation

$$R_t = \sqrt{\frac{L}{C}}$$

at 500 ohms.

75 A hundred feet of this line is found to trans-

mit signals over the entire broadcast band with a negligible amount of attenuation. The length of each section of the line is not critical. It may be varied 25% with no bad effects.

It now remains to design a suitable transformer to match the plate impedance of the tube (10,000 ohms) to the 500 ohm line load. This requires a stepdown ratio of $\sqrt{20}$ or about 4.5 to 1. Since it is impractical to build a transformer that is 100% coupled, the leakage reactance thereof appears as the loading inductance of the first section of the line. The inductance of the primary must be great enough to make an effective transformation at the lowest frequency of the band.

Two millihenries is found sufficient for the primary. That portion of the secondary which may be considered 100% coupled to the primary must accordingly have an inductance of

$$20 \quad \frac{.002}{20}$$

or 100 microhenries. Adding to this the leakage reactance of 100 microhenries gives a transformer with a 2000 microhenry primary winding, a 200 microhenry secondary winding, 50% coupling, and an effective ratio of 4.5 to 1.

It should be noted that the tube plate-filament capacity, (10 mmmfd. usually), multiplied by the square of the turns-ratio, (i. e., 20) supplies the correct terminal capacity for the low-pass filter, 200 mmmfd.

The design of the output transformer of the apartment coupling tube is obtained by following a similar line of reasoning. Its ratio is about 2.25 to 1. This matches the tube impedance with an impedance of 2000 ohms, which seems to be a good average value for the input impedance of receivers of various types.

If one volt of radio-frequency voltage is applied on the grid of the antenna-coupling tube, and the amplification factor of the tube is 9, we have

$$40 \quad 1 \times 9 \times \frac{1}{4.5} \times \frac{1}{2} \times \frac{1}{2} = \frac{1}{2}$$

45 volt applied to the grids of the apartment-coupling tubes, assuming no attenuation. If the input impedance of the radio receiver is 2000 ohms, in order to provide an impedance matching the impedance of the apartment-coupling tube as seen from the transformer, $\frac{1}{2}$ volt applied to the grid of the said tube will develop 1 volt across the input circuit of the receiver. If the impedance of the receiver is other than 2000 ohms the input voltage may be greater or smaller but operation is fairly satisfactory. To make the impedance of the transformer 36 more nearly like that of an antenna, a small condenser 50 may be serially included between the secondary windings thereof and the terminals 40 and 41.

50 Thus, the system provides signals at each receiver outlet plug that will be the equivalent of those which would be obtained if the receiver were located on the roof of the building and were the only one supplied from the antenna.

55 It will thus be seen that I have provided a radio-frequency signal-distribution system whereby a single energy-collecting device may be utilized to provide a plurality of remotely-situated radio receiving sets with an unlimited number of programs distributed by radio-frequency current, each program being selectable by the individual sets at the option of the operator without influencing the reception of other programs by the remaining sets. In addition, proportion-

ing the electrical constants of the individual transmission lines according to my invention, each line is given the characteristics of a band-pass filter which transmits with substantially equal efficiency all of the radio-frequencies lying within the range for which the system is designed.

Another important advantage of my invention lies in the fact that the shielded transmission lines do not pick up electrical disturbances originating in sparking at elevator-control contacts, and similar interfering impulses. In fact, a radio set coupled to the distribution system is actually quieter in operation than a similar set coupled directly to an antenna of the usual type, since the "pick-up" that would be present with an unshielded down-lead is eliminated by the shielding.

Inasmuch as many modifications of the specific apparatus chosen for illustrative purposes will be apparent to those skilled in the art, my invention is not to be construed as restricted thereto, but is to be limited only by the prior art and by the spirit of the appended claims.

The manner in which plate-potential for the individual apartment-coupling tubes is transmitted from a central source, in accordance with my invention, is also considered an important feature of the system since the said coupling tubes may thus be kept supplied with potential, without attention on the part of the tenant of the apartment.

I claim as my invention:

1. In a signal receiving and distributing system, means for amplifying signals at radio-frequencies, a transmission line having the characteristics of an electrical filter for conveying said signals to a plurality of remote points, additional amplifying means associated with said line at said remote points, and means for utilizing said line for the transmission of direct currents to said amplifying means.

2. In a signal-distributing system, a transmission circuit including a plurality of sections having inductance and capacity, a thermionic device, and means for so associating said thermionic device with said line that the plate-filament capacity of said device furnishes the capacity for the initial section of the line, said means also providing the inductance for said initial section.

3. In a system for the distribution of radio programs in an apartment house, a transmission line including a plurality of sections having loading inductance, a thermionic device, and a transformer interposed between said device and said line, the leakage reactance of the secondary winding of said transformer being substantially equal to the said loading inductance.

4. A multiplex high frequency receiving system for operating a plurality of receiving devices from the same energy pickup device, comprising, in combination, means for picking up high frequency energy to be received, a line conductor associated with said pickup for transmitting energy to all of said receiving devices, said receiving devices being connected through an impedance to said conductor at intervals, and loading coils interposed in said conductor intermediate said receiving devices, said line conductor being grounded at its end through a resistance of such value as to substantially prevent the production of standing waves on said line.

5. A multiplex high frequency receiving system for operating a plurality of receivers from the same energy pickup device, comprising, in com-

bination, means for picking up high frequency energy to be received, a transmission line associated with said pickup means, said line being positioned within an enclosing conductor through at least a portion of its length and being loaded at predetermined points to act as a uniform attenuation line passing energy of frequencies up to the highest desired frequency, and a plurality of receivers coupled to said line at points electrically intermediate to said loaded points.

6. A multiplex high frequency receiving system for operating a plurality of receiving devices from the same energy pickup device, comprising, in combination, means for picking up high frequency energy to be received, a line conductor associated with said pickup for transmitting energy to all of said receiving devices, said line conductor being surrounded by a metallic conductor through at least a portion of its length, said receiving devices being connected to said conductor at intervals, and loading coils interposed in said conductor intermediate said receiving devices, said line conductor being grounded at its end through an impedance of such value as to substantially prevent the production of standing waves on said line.

7. A multiplex high frequency receiving system for operating a plurality of receiving devices from the same energy pickup device, comprising, in combination, means for picking up high frequency energy to be received, a line conductor associated with said pickup and leading to said receiving devices, means for connecting said receiving devices to said line in energy absorbing relation, said line conductor being enclosed throughout a portion of its length within a conducting casing, and loading coils interposed in said conductor intermediate said receiving devices, the structure of said system being such that said line conductor has an electrically infinite effective length, and the constants of said loading coils having a value such that said line exhibits the characteristic of a uniform attenuation line passing currents of a frequency as high as the highest frequency desired to be received.

8. A multiplex radio receiving system comprising an antenna mounted in position to pick up energy to be received, a line conductor serving a plurality of receivers, means for connecting a plurality of said receivers to said line in energy absorbing relation, loading coils interposed in said line between adjacent receivers to cause said line to have the characteristics of a uniform attenuation line passing all frequencies desired to be received, means for preventing terminal reflection on said line, and said line conductor being enclosed within a grounded metallic conduit.

9. A radio receiving system for protecting a receiver from local interference comprising, in combination, an antenna for collecting signal energy to be supplied to a receiver, a lead-in, a radio receiver operatively associated with said lead-in, a grounded conductor enclosing said lead-in for a substantial portion of its length and insulated therefrom, and maintained at ground potential, and a transformer interposed between the head of said lead-in and said antenna.

10. In a radio receiving system for protecting a receiver from local interference, in combination, an antenna for collecting signal energy to be supplied to a receiver, a lead-in, a radio receiver operatively associated with said lead-in, and a transformer interposed between the head of said lead-in and said antenna, said transformer

9

2,094,360

5

and said lead-in being enclosed within a conducting container maintained at ground potential.

11. In a radio receiving system for protecting a receiver from local interference, in combination, an antenna for collecting signal energy to be supplied to a receiver, a lead-in, said lead-in being enclosed within a grounded conducting container, a radio receiver, means for connecting

said radio receiver to said lead-in in operative relation, and means interposed between said antenna and said lead-in for maintaining a uniform energy transfer relation between said antenna and said lead-in over a relatively wide band of frequencies.

VERNON D. LANDON.
